UNITED STATES PATENT OFFICE

2,195,368

WEATHER STRIP

Joseph Philander Hasty, Wichita, Kans.

Application September 23, 1937, Serial No. 165,387

1 Claim. (Cl. 20—68)

This invention aims to provide novel means for imparting vertical movement to a closure member at the lower edge of a door, thereby to close the space between the lower edge of the door and the threshold. The invention aims to supply novel means for mounting the closure member yieldably and for actuating it.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in horizontal section, a device constructed in accordance with the invention; Fig. 2 is a vertical section on the line 2—2 of Fig. 1;

Fig. 3 is a transverse section;

Fig. 4 is an elevation showing part of the closure member.

Fig. 5 is a sectional view of a modified arrangement.

The numeral 1 marks one jamb of a doorway, carrying an abutment strip 2. The opposite jamb of the doorway is marked by the numeral 3 and carries an abutment strip 4 provided with an angular wear plate 5. A door 6 is hinged at 7 to the jamb 1 and closes against the abutment strips 2 and 4.

The numeral 8 designates an elongated box-like casing, preferably made of metal. The casing 8 is closed at both ends, at the front and at the top, but is open at the back and at the bottom. The casing 8 has an upstanding flange 9 adapted to receive securing elements 10 whereby the casing 8 is fastened to the door 6. The casing 8 is supplied at its ends with flanges 11 which, also, are secured to the door 6. In order to make the casing 8 longitudinally adjustable to fit doors of different widths, the casing is composed of parts which are telescoped with respect to each other, as shown at 11. The outer wall of one part of the casing 8 carries a clamping device, such as a bolt 12, adjustable in a horizontally elongated slot 14 formed in a corresponding wall of the other part of the casing. The inner ends

of the flange 9 are overlapped on each other. One of said ends of the flange 9 carries a clamping device, such as a bolt 15, adjustable in a slot 16 in the other part of the flange, as shown in Fig. 1. Without further description, it will be understood that the casing 8 is adjustable as to length.

In its ends, and close to the door 6, the casing 8 is supplied with slots 18 receiving the reduced ends 20 of a closure member 19, preferably in the form of a plate, slideable in contact with the door 6, vertically. The closure member 19 is made in two parts which are overlapped on each other, so that the closure plate, like the casing 8, may be adjusted as to length. One part of the closure member 19 carries a clamping device or bolt 21, adjustable in a slot 22, in the other part of the closure plate.

Fixed horizontal tracks 23, which may be angle members, are secured to the closure plate 19 near to the ends thereof. Below the tracks 23 are disposed spring tongues 24, each of which is secured at one end, as shown at 25, to the closure plate 19. The front wall of the casing 8 carries rearwardly projecting brackets 26, whereon depending bell cranks 28 are fulcrumed intermediate their ends, as shown at 27. Each bell crank 28 includes a first arm 29 and a second arm 30 having a lateral finger 100. On the finger 100 of each bell crank is journaled a roller 31 which operates between one of the spring tongues 24 and the corresponding track 23.

Disposed within the casing 8 is an operating member 32, preferably made in two parts, so that it can be adjusted as to length, like the casing 8 and the closure plate 19. One of the parts of the operating member 32 is supplied at its inner end with a socket 34, in which the corresponding end of the other part of the operating member is received for longitudinal adjustment. Said other part of the operating member 32 carries a clamping device 36, such as a bolt, adjustable in an elongated slot 35 in the socket 34. The second arms 29 of the bell crank lever 28 are pivotally mounted at 33 in the operating member 32. A head 37 is secured to one end of the operating member 32. The head 37 is adjustable longitudinally of the operating member 32, and with this end in view, the head 37 has an elongated slot 38, receiving a clamping and securing device 39 mounted in the correspondingly adjacent portion of the operating member 32.

One end of a link 40 is pivotally mounted at 41 in the head 37. The opposite end of the link 40 is pivotally mounted at 42 in one arm of a

hollow actuating lever 43, mounted to swing horizontally on a shaft 44 carried by ears 45 struck from the adjacent end wall of the casing 8. The actuating lever 43 works through the opening 46 in the end of the casing 8. A spring 47 is coiled around the shaft 44, within the actuating lever 43, one end of the spring bearing against the actuating lever, and the opposite end of the spring bearing against the outer wall of the casing 8. The function of the spring 47 is to swing the actuating lever 43 outwardly through the opening 46 in the end of the casing 8, when the door 6 is opened from the position shown in Fig. 1.

15 The device will operate regardless of whether the left hand edge or the right hand edge of the door is the hinged edge. A comparison of Figs. 2 and 5 will make manifest the correctness of the foregoing statement.

20 In practical operation, when the door 6 is closed, as in Fig. 1, the actuating lever 43 engages the wear plate 5 on the abutment strip 4, and the actuating lever is swung on its fulcrum shaft 44. The actuating lever 43 operates the link 40, the 25 operating member 32 is carried to the right, and the bell crank levers 28 are swung on their fulcras 27, the rollers 31 on the second arms 30 of the bell crank levers 28 carrying the closure member 19 downwardly to the position of Fig. 3, and holding it in that position yieldably, because the 30 spring tongues 24 are flexed by the operation of the rollers 31 on the second arms 30 of the bell crank levers.

35 When the door 6 is opened, the actuating lever 43 no longer is pressed against the wear plate 5 on the door frame, and the actuating lever swings to the left in Fig. 1, under the impulse of the spring 47. The link 40 imparts longitudinal movement to the operating member 32 to the left in Fig. 2, the rollers 31 on the arms 30 of the bell crank levers 28 engage the tracks 23 on the closure member 19, and the closure member is raised.

40 Because the closure plate 19 has reduced parts 20, which extend outwardly through the slots 18 in the ends of the casing 8, the reduced parts 20 overlap the abutment strips 2 and 4, and practically close the spaces between the ends of the casing 8 and the abutment strips, the construction having a manifest advantage over one in which the closure plate works entirely within the casing, the aforesaid spaces being left opened.

45 It is to be observed that the closure plate 19 is located at the extreme back of the casing 8, in contact with the door 6, and as far as possible from the outer wall of the casing 8, as Fig. 3 will show. It is at the outer wall of the casing 8 that snow and ice collect, but the closure plate 19 is set far enough back from the outer wall of the casing 8 so that snow and ice are not likely to collect against the lower part of the closure plate and freeze it fast to the threshold.

50 In assembling the device, the actuating lever 43 should project out of the end of the casing 8 the proper amount, and at the same time, the lower edge of the closure plate 19 ought to be positioned properly with respect to the lower edge of the door 6. In order to obtain this relation,

5 there has to be expended in the making of similar articles, a degree of accuracy not profitable in connection with a cheap article of the class described. The difficulty is circumvented by making the head 37 adjustable longitudinally of the 5 operating member 32.

A reason has been set forth hereinbefore for having the closure plate 19 set well back from the outer wall of the casing 8, and it is not practical to lengthen the horizontal part of the 10 bracket 26 and put the bell crank 28 between the track 23 and the spring tongue 24, because if that were done, the angle of the bell crank would have to be increased to practically 180 degrees, and such a bell crank or lever would not function 15 properly. Since the bell crank 28 has to be located to one side of the track 23 and the spring tongue 24, as shown in Fig. 3, the bell crank has to be provided with the laterally and inwardly extended finger 100, whereon the roller 20 31 is journaled. If it were possible to place the bell crank lever 28 between the track 23 and the spring tongue 24, the track 23 could be replaced by a mere projection or pin, since such an element could ride along one arm of the bell crank. 25 Considering, however, the fact that the bell crank lever 28 has to have the finger 100, a projection or pin, used in place of the track 23, would have to be located with considerable accuracy. No such accuracy is needed when the 30 elongated track 23 is used.

Having thus described the invention, what is claimed is:

In a device of the class described, a casing including a front wall and end walls, the end walls 35 having vertical slots in their lower edges, a closure provided at its lower corners with reduced parts extending outwardly through the slots to bridge the spaces between the end walls of the casing and the jambs of a door frame, the closure being located at the extreme back of the casing, whereby the front wall of the casing will constitute a weather-stop for the closure and lessen the chance of the lower edge of the closure freezing to a threshold, an elongated track carried by the closure and extended longitudinally thereof, a spring carried by the closure and extended longitudinally thereof, the spring being located below the track and being spaced from the track, an operating member movable longitudinally of the casing, a bell crank lever fulcrumed on the casing in front of the track and the spring, means for pivoting one arm of the bell crank lever to the operating member, means cooperating with the spring to depress the closure 45 yieldably and cooperating with the track to raise the closure positively, the last-specified means comprising a laterally prolonged finger on the other arm of the bell crank lever and extended between the spring and the track, a jamb-engaging lever fulcrumed on one end of the casing, a link pivoted to the last-specified lever, a head mounted on said operating member for adjustment longitudinally thereof and pivotally connected to said link whereby pivotal movement of 55 said last-specified lever operates to move the closure.

JOSEPH PHILANDER HASTY.
